UNITED STATES PATENT OFFICE

132,462

DESIGN FOR A COMBINED BUTTER KNIFE AND BUTTER PICK OR SIMILAR ARTICLE

Edwin Reynolds, Vineland, N. J.

Application December 10, 1941, Serial No. 104,554

Term of patent 14 years

To all whom it may concern:

Be it known that I, Edwin Reynolds, a citizen of the United States, residing at Vineland, in the county of Cumberland and State of New Jersey, have invented a new, original and ornamental Design for a Combined Butter Knife and Butter Pick or Similar Article, of which the following is a specification, reference being had to the accompanying drawing, forming part thereof.

Fig. 1 is a side elevational view of a combined butter knife and butter pick or similar article, showing my new design.

Fig. 2 is a plan view thereof.

Fig. 3 is a front elevational view, and
Fig. 4 is a sectional view taken on line 4—4 of
Fig. 1.

The opposite side of the device is similar to that shown.

I claim:

The ornamental design for a combined butter
knife and butter pick or similar article, substantially as shown and described.

EDWIN REYNOLDS.
